UNITED STATES PATENT OFFICE.

CHARLES L. METZLER, OF NEWARK, NEW JERSEY, ASSIGNOR TO UTILITY ACCESSORIES CORPORATION, OF NEW YORK, N. Y., A CORPORATION OF NEW YORK.

DESIGN FOR ADVERTISING VENDING-MACHINE CABINET.

Application filed February 7, 1924. Serial No. 8,563. Term of patent 7 years.

To all whom it may concern:

Be it known that I, CHARLES L. METZLER, a citizen of the United States, residing at Newark, in the county of Essex and State of New Jersey, have invented a new, original, and ornamental Design for an Advertising Vending-Machine Cabinet, of which the following is a specification, reference being had to the accompanying drawing, forming part thereof.

The figure is a perspective view illustrating the invention.

I claim:

The ornamental design for advertising vending machine cabinet as shown.

CHARLES L. METZLER.
